COMBINATION BATH ROOM UNIT

David W. Klibanow, Chicago, Ill.

Application November 21, 1957, Serial No. 48,578

Term of patent 14 years

(Cl. D4—4)

Fig. 1 is a perspective view of a combination bath room unit, the tub being in covered condition to serve as a floor mat, showing my new design;

Fig. 2 is a perspective view thereof showing the floor mat which constitutes a tub cover in position for use as a bathtub.

The dominant features of my design reside in the portions shown in full lines.

I claim:

The ornamental design for a combination bath room unit, as shown and described.
